PACKAGE FOR CIGARS OR THE LIKE

Bernard J. Tamarin, Whitemarsh, Pa., assignor, by direct and mesne assignments, to Pull-Packaging, Inc., Philadelphia, Pa., a corporation of Pennsylvania

Filed Apr. 8, 1964, Ser. No. 79,398

Term of patent 14 years

(Cl. D58—12.6)

Fig. 1.

Fig. 2.

Fig. 3.

FIG. 1 is a top front perspective view of a package for cigars or the like, showing my new design;

FIG. 2 is a bottom rear perspective view thereof taken from the side opposite that shown in FIG. 1; and

FIG. 3 is a fragmentary front elevational view of the top of FIG. 1.

The package is broken away to show indeterminate length.

I claim:

The ornamental design for a package for cigars or the like, as shown and described.
